UNITED STATES PATENT OFFICE.

ALEXANDER FORBES, OF HAMPSTEAD, LONDON, ENGLAND.

TRUNK AND OTHER ARTICLES WITH LIDS.

1,079,981.

Specification of Letters Patent.

Patented Dec. 2, 1913.

Application filed December 30, 1912. Serial No. 739,818.

To all whom it may concern:

Be it known that I, ALEXANDER FORBES, a subject of the King of Great Britain, residing at Hampstead, in the county of London, England, have invented new and useful Improvements in Trunks and other Articles with Lids, of which the following is a specification.

This invention relates to trunks, cases and other articles provided with lids.

It is the object of the invention to provide a connection between such articles and their lids which will allow the lids to be opened with a sliding movement as well as a hinging movement, or with either, and will permit the lids to slide down and stand in an approximately vertical position at the back of the trunks or other articles of which they form a part.

20 A further object is to provide substantial hinges with sliding connections between said hinges and the lids.

Other objects and improvements will be made clear by the following description.

25 In the drawings:—Figure 1 is a partial front view of a portion of a trunk and its lid showing a hinge applied thereto. Fig. 2 is a vertical section on the line A—B of Fig. 1. Fig. 3 is a cross section on the line C—D of Fig. 2. Figs. 4, 5, 6 and 7 are detail views showing various sections of guide members and slides engaging therewith. Figs. 8, 9 and 10 are end views of a cabin trunk to which the invention has been applied, illustrating three ways in which the lid may be opened. Fig. 11 is an isometric view of such a cabin trunk with the lid closed. Fig. 12 is an isometric view of a round topped trunk or case showing the application of the invention thereto. Fig. 13 is a detail view showing a section of the guide member of Fig. 12. Figs. 14 and 15 are sectional and face views respectively illustrating an adjustable stop which may be used to limit the backward sliding movement of the lid.

Referring first to Figs. 1, 2 and 3, a represents part of a trunk to which a hinge member *b* is fitted, this hinge member being passed through the trunk wall at the shoulder or embushment thereof and suitably secured by means of rivets or otherwise. The top of the member *b* is provided with an extension *c* which is bent over and secured around the edging *d* of the trunk top. The edging and the middle part of the extension

e are cut away or depressed as shown, to accommodate the hinge member *e* when the lid is closed. This member *e* is hinged to the member *a* at *f*, and is bent to elbow form and strengthened by an angle piece *g* at the bend as shown in Fig. 2. A guide piece *h* affixed to the hinge member *e* works over a guide bar *i* which is attached inside the lid *k* of the trunk. There are usually two such hinges and guide bars for each trunk lid. The members *h* and *i* may be made of any suitable cross section, a number of these being indicated in Figs. 3 to 7. The form of Fig. 3 is usually preferred, as it can be made from sheet metal by a simple drawing process. Any other suitable section may be used of course, and balls *l* may be inserted in notches in the member *h* as shown in Fig. 7, in order to facilitate the sliding of the parts one over the other.

The advantages of connecting the lid to the body of the trunk by this type of sliding connection are well illustrated in Figs. 8, 9 and 10. In this type of cabin trunk, the lid *k* has a flap or staff *m* at the front, which normally lies flat against the front of the trunk to which it is held by hasps or catches of any suitable type when the lid is closed (see hasps *o* in Fig. 11 for instance). When the trunk is being packed it is convenient to have the lid dropped back into the position of Fig. 8 by the bars *i* sliding through the hinge guides *h*, thus giving easy access to the whole interior of the trunk, and avoiding any risk of the accidental closing of the lid; or the lid can be opened if required with a hinging movement only as in Fig. 10. When the trunk is used in a confined space however, as for instance beneath a cabin berth *n* as in Fig. 9, the trunk can be pulled out and the lid pushed or held back as shown, so that the trunk can be used like a drawer and there is no necessity to pull it completely out from under the berth in order to open the lid, as is the case with cabin trunks having lids as usually made hitherto.

Fig. 11 shows a cabin trunk with the lid closed and locked by hasps *o*, which also help to hold the hinged flap *m* closed down. Straps and buckles *p* are provided in this case for securing the ends of the flap *m* when the trunk lid is closed for transit.

The invention is not limited in its application to cabin trunks, but it is applicable also to cases, boxes and other articles with

lids for any suitable purpose. It is shown for instance as applied to a trunk with a rounded or domed top in Fig. 12. Guide bars *q* of a section such as that shown in Fig. 13, are attached to boards *r* which fit in the domed lid *k* and are held in place for instance by brackets *s*, which may be fitted in grooves in the boards *r* as indicated in Fig. 13. The hinges may be the same as in Figs. 1 and 2. The space between the boards *r* may be open, while a tray *t* (shown removed) may be inserted to fill the space. It is not usually desirable that a lid of a trunk of this type should fall quite back until it rests on the floor, as it may be heavy to lift. It is preferable therefore, to provide suitable stops such as metal studs *u* riveted in the guide bars *q* (Fig. 13) to arrest the backward movement of the lid when it reaches the position of Fig. 12, by coming against the ends of the hinge guides *h*. Alternatively, cords or chains attached to studs *v* on the hinge member *e* and to suitable points on the lid may be used to serve the same purpose (as shown by dotted lines *w* in Fig. 12). It may be preferable in some cases to have stops which can be brought into action at will, instead of permanently fixed stops such as *u*. Figs. 14 and 15 show such a stop consisting of a pin *x* with a T-shaped head which can lie in a slot *y* in the bar *q* as in Fig. 15, or can be pulled out and stood across the slot *y* so as to project from the bar *q* as in Fig. 14. A spring *z* normally holds the pin in the slot *y*.

The trunk lid made as shown in Fig. 12 has no hinged staff or flap at the front, so it has to be lifted slightly in opening the lid in order to raise it over the front edge of the trunk before the lid can be pushed back. It will then go back with a combined sliding and hinging movement to the position of Fig. 12. It is drawn forward again by a similar movement, and it is very easy to close as it is practically pivoted at its middle part when open, so that the energy required to pull it over forwardly on to the top of the trunk before pulling it along horizontally to close it, is very slight.

Finally, it will be evident that lids with sliding hinges of the type set forth can be applied to articles of any kind requiring lids which may advantageously slide in this way.

Modifications may be made in the details of construction without departing from the scope of the invention.

I claim:

60 1. The combination with a receptacle hav-

ing a lid, of hinge supports attached to the receptacle, hinge members mounted to turn on said hinge supports, guides on said hinge members, bars affixed to the inside of the lid, said bars being adapted to engage with and slide in the guides, the engagement of the bars with the guides being such that the bars can slide in the guides in any position of the hinge supports. 65

2. The combination with a receptacle and a lid therefor formed with turned down edges, of hinges pivotally mounted on the receptacle and having turning parts of elbow shape with guides formed on the outer portions thereof, and bars attached to the inside of the lid adapted to slide upon said hinge guides, the engagement of the bars with the guides being such that the bars can slide in the guides in any position of the hinge supports. 70

3. The combination with a receptacle and a lid therefor formed with edges adapted to fit over the edges of the receptacle, the front edge of the lid being in the form of a flap adapted to be turned out to lie in the plane of the lid, hinges attached to the receptacle and sliding connecting means between the hinges and the lid. 75

4. The combination with a receptacle, of hinges attached to the receptacle, a lid and sliding connecting means between the lid and hinges, said lid comprising a cover for the receptacle, edges to fit around the edges of the receptacle at three sides thereof, a flap at the fourth side pivotally connected to the lid, and means for fastening said flap in a position to fit against the face of the receptacle when the lid is closed thereon. 80

5. The combination with a receptacle having a lid, of hinges therefor, attached to the receptacle, guides forming part of said hinges, bars affixed in the lid adapted to work upon said guides on the hinges, a stop member on each bar comprising a headed pin, a spring adapted to hold said pin normally with its head retracted, the head of said pin when drawn out being adapted to come against the hinge guide and to limit the sliding of the bar thereupon. 100

6. In combination a receptacle, a recessed lid therefor, two bars attached inside the lid, and two hinges attached to the receptacle, each hinge having its turning portion of elbow shape and provided on the outer part thereof with a guide to fit one of the bars. 105
